UNITED STATES PATENT OFFICE

168,690

EGG SERVER

Leonard Kalt, New York, N. Y.

Application September 25, 1952, Serial No. 21,583

Term of patent 7 years

(Cl. D44—9)

To all whom it may concern:

Be it known that I, Leonard Kalt, a citizen of the United States, a resident of the city of New York, in the county of Queens and State of New York, have invented a new, original, and ornamental Design for an Egg Server, of which the following is a specification, reference being had to the accompanying drawing, forming a part hereof.

Fig. 1 is a top view of an egg server embodying my new design;

Fig. 2 is a side view;

Fig. 3 is a bottom view;

Fig. 4 is a perspective view.

I claim:

The ornamental design for an egg server, substantially as shown.

LEONARD KALT.
